PART FOR KNITTING MACHINES

De Hart G. Scramton, Maplewood, N. J., assignor
to Western Electric Company, Incorporated,
New York, N. Y., a corporation of New York

Application August 25, 1943, Serial No. 499,878

7 Claims. (Cl. 66—116)

This invention relates to parts for knitting machines and has for its object the provision of new and improved parts for knitting machines.

In knitting machines, jacks which hold knitting needles and raise and lower the needles are provided with needle-receiving slots. In jacks heretofore known, these slots and needles held thereby become worn after they have been in use for some time, thereby permitting movement between the needles and the jacks, which often causes the needles to strike the thread guide and become broken.

One structure embodying the invention comprises a jack having a notch formed therein for receiving a nib on a knitting needle to resiliently hold the needle and also provided with an elongated slot connecting with the notch which gives the lips of the notch sufficient resiliency to engage the nib at all times and hold the needle firmly in place.

Other objects and features of the invention will become apparent from the following detailed description when read in conjunction with the drawing, in which

Fig. 1 is a fragmentary side view in partial section of one embodiment of the invention;

Fig. 2 is a sectional view of the apparatus taken along the line 2—2 in Fig. 1, and

Fig. 3 is a fragmentary side view in partial section of an alternative embodiment of the invention.

In accordance with one embodiment of the invention, a jack 10 has a notch 11 formed in one end thereof. The jack is also provided with an elongated slot 12 extending inwardly from the notch 11 terminating in a circular aperture 13. Jaws 14 and 15 formed upon the end of the jack 10 by the notch 11 are resiliently movable with respect to each other by reason of the slot 12 and the aperture 13. Except for the above described features, the jack 10 is of conventional design.

A needle 16 of conventional design having a nib 18 also of conventional design formed thereon, is slidably mounted in the usual manner in a slot 19 formed in a block 20 comprising a part of a knitting machine. Surfaces 21 and 22 formed on the jaws 14 and 15, respectively, are complementary to and bear against surfaces 24 and 25 formed on the nib 18 when the latter is positioned therebetween.

After the jaws 14 and 15 have been drawn apart and the nib 18 inserted therebetween, the jaws 14 and 15 are released and their resiliency forces them together to firmly grip the nib 18, which is somewhat wider than the notch 11. If

the contacting surfaces 24 and 25 of the nib 18 and the surfaces 21 and 22 of jaws 14 and 15 should become worn, the resiliency of the jaws will draw them closer together to continue to securely hold the nib 18 and thereby prevent relative movement between the jack 10 and the needle 16 during the knitting operation, thus preventing breakage of the needle. The jack is reciprocated rapidly by conventional means (not shown) to cause the needle to engage and disengage a strand to form a knitted fabric in accordance with the usual operation of knitting machines.

In an alternative embodiment of the invention, which is shown in Fig. 3 of the drawing, a reciprocating jack 40 has formed therein an L-shaped notch 41 and an elongated slot 42 connected with the notch 41 and a circular aperture 43 to form jaws 44 and 45 thereon. The jack 40 is similar to the jack 10 except for the configuration of the notch 41 and the jaws 44 and 45.

A needle 46 having an L-shaped nib 47, which includes a projection 48, formed on the lower end thereof, is similar to the needle 16 except for the nib 47 and is reciprocably mounted in a slot 49 formed in a block 50. The block 50 and the slot 49 formed therein are of conventional design and are similar to the slot 19 and the block 20. The jaws 44 and 45 have surfaces 52 and 53 formed thereon which are complementary to surfaces 54 and 55 formed on the nib 47.

In assembling the needle 46 and the jack 40, the jaws 44 and 45 are opened sufficiently to insert the nib 47 into the notch 41 and the jaws 44 and 45 are released to firmly and resiliently grip the nib 47 with the surfaces 52 and 53 of the jaws bearing against the surfaces 54 and 55 of the nib 47, thereby preventing play between the needle and the jack. If the needle 46 should be twisted during the knitting operation, projection 48 strikes the jaw 44 and prevents the nib 47 from being twisted out of the notch 41. If the jaws 44 and 45 or the nib 47 become worn, the resiliency of the jaws will nevertheless cause the jaws to firmly grasp the nib 47 and prevent relative movement therebetween, and thereby prevent breakage of the needle.

It will be readily seen that the constructions of the jaws and needles described above eliminate breakage of needles and the consequent delay in production, expense and waste of labor and materials, and thus increase the usefulness and longevity of both the needles and the jacks.

What is claimed is:

1. A knitting jack for holding a nib of a knit-

ting needle, which comprises an arm having an orthogonal notch formed in one end thereof to form a pair of jaws having straight gripping surfaces for gripping a straight surfaced nib of a knitting needle, and also being provided with an elongated slot connecting with the notch to give the jaws sufficient resilience to firmly grip the nib.

2. A jack for holding a nib of a knitting needle, which comprises an arm having an oblong notch formed in the end thereof to form jaws for grasping a nib of a knitting needle positioned in said notch and also provided with an elongated slot to give the jaws resiliency, said jaws having surfaces formed thereon complementary to surfaces formed on the nib.

3. A jack for holding a nib of a knitting needle, which comprises an arm having an L-shaped notch formed therein to form a pair of jaws for clamping an L-shaped nib of a knitting needle positioned in said notch, and also provided with an elongated slot connected with said notch to provide the jaws with sufficient resilience to firmly grasp the nib therebetween.

4. A jack for holding knitting needles, which comprises an arm having an L-shaped notch formed therein to form a pair of jaws for clamping an L-shaped nib of a knitting needle therebetween, the base of said L-shaped notch fitting

5 closely around the end of the nib so as to prevent longitudinal twisting of the needle with respect to the jaws.

5. In a knitting machine, the combination of a knitting needle comprising a shank having an L-shaped nib formed thereon, and a jack having an arm formed thereon, said arm having an L-shaped notch formed therein to form a pair of jaws complementary to said L-shaped nib for holding the nib and for preventing longitudinal twisting of the needle with respect to the jaws.

6. In a knitting machine, the combination of a knitting needle comprising a shank having an L-shaped nib formed on one end thereof, and a jack comprising an arm having an L-shaped notch formed in the end thereof for receiving the nib of the knitting needle and having an elongated slot therein connected with said notch to cause the sides of the notch to resiliently engage said nib.

7. A jack for holding nibs of knitting needles, which comprises an arm having a notch therein forming a pair of jaws, said notch having straight sides at the mouth thereof to provide straight gripping surfaces at the ends of the jaws, said arm also being provided with a slot extending from the notch to give the jaws resiliency.
